TRAM CAR FOR MINE DRILLS

William B. Manning, Taylorville, Ill.

Application February 26, 1948, Serial No. 11,158

3 Claims. (Cl. 255—51)

1

This invention relates to tram-cars for mine drills, and the main object of the invention is to provide a practical and efficient tram car for use in moving mining drills along the horizontal shafts and galleries of a coal mine or the like, where drilling operations are under way.

Another object of the invention is to provide in compact form a practical tram-car for expeditiously transporting conventional forms of mining drills from one location to another along the shafts and galleries of a mine, such as a coal mine, whereby drilling operations may be speeded up and time saved.

Another object of the invention is to provide a tram-car of the kind referred to, the same including a suitable wheel-borne and steerable, motor driven chassis, a tonneau with seats and electrical control and operating elements mounted at the forward end of the chassis, a tool box mounted at the rear end thereof, and pedestal plates mounted upon the sides of the chassis for operatively supporting drilling apparatus in convenient position for such drilling operations.

With the stated objects in view, together with such additional objects and advantages as may appear from the specification, attention is called to the accompanying drawing as illustrating a preferred form of the tram-car, and wherein

Figure 1 is a plan view of the tram-car, showing the construction of the chassis and accessories and showing conventional forms of mining drills mounted thereon and shown in their lowered positions.

Figure 2 is a side elevation of the assembly as shown in Figure 1.

Figure 3 is a section on the line 3—3 of Figure 1.

Figure 4 is a section on the line 4—4 of Figure 1.

The tram-car as constructed in accordance with this invention comprises an oblong chassis referred to generally at 5, the same including channelled side beams 5a, and plates 5b, cross braces 5c, and floor 5d, the material used for these structural elements being channel iron, angle iron, sheet iron or the like, or any other suitable material, all assembled in proper form by welding, riveting, bolting, or other conventional means and methods.

The chassis 5 is carried upon pairs of front and rear wheels 6 and 7, the front wheels being journaled upon spindles 8 which are formed with and merge integrally at their inner ends into heavy, upstanding pivot pins 8a, and with horizontally and rearwardly extended steering arms 8b, the latter being formed at their free ends with vertically apertured heads 8c. The pivot pins 8a are

seated freely upwardly in sleeves or sockets 9a formed in the ends of the rigidly mounted axle or cross member 9, anchored to and suspended from the side beams 5a of the chassis 5. A pair of short and transversely extended steering arms 10 are provided, the same having vertically apertured heads 10a at their outer ends for positioning below the heads 8c of the arms 8b, after which bolts 11 are passed through these heads and nuts are turned upon the threaded ends of the bolts for operatively locking these elements together. The opposite inner ends of the arms 10 are threaded for adjustably engaging longitudinally bored and tapped yoke-links 12 which are bifurcated at 15 their opposite inner ends as at 12a, so that one may be overlapped upon the other, as clearly shown in Figure 3, after which they are pivotally pinned together by a bolt 13 passed through their apertured and overlapped ends. A steering post 14 is medially, vertically and pivotally mounted upon the vertically extended cross-plate 15 which is anchored at its ends laterally to the side beams 5a, by means of bearing or pivot blocks 16 bolted at 16a, in vertical alignment upon the rear side 20 of the plate 15, and through which recessed blocks the post 14 is freely extended. A short, flat and integrally formed control plug 14a is extended horizontally rearward from the lower end of the post 14, the outer end thereof being slotted as at 25 14b and being positioned between the forks 12a of the inner yoke link 12, with the bolt 13 passed through the said slot 14b. A steering lever or handle 14c is extended straightly forward from the upper end of the steering post 14. With the construction shown, the moving of the handle 14c to the left or right serves to steer the tram-car likewise. The front wheels 6 are mounted relatively closer together than the rear wheels 7 and are cambered or "toed" inwardly, for the purpose of 30 facilitating the operation of the vehicle within the galleries and shafts of a mine. The plate 15 is cut away as shown in Figure 3, to accommodate the front wheels.

A bench-plate 17 is extended flatly across the 35 side beams 5a forwardly of the plate 15, and is anchored at its ends to the beams. At this forward end of the car the bottom is lowered as at 5e and is supported in place by the downwardly extended and connected side plates 5f which depend at this end from the side beams 5a and to which beams the side plates are anchored. A pair of seat or bench-plates 18 are mounted in place along the forward ends of the beams 5a and are rigidly secured thereto at their outer margins. 40 These arrangements complete the operator's ton-

neau at the forward end of the car. The bottom 5e of this tonneau, between the seats 18, provides space for coiling and carrying the rubber power line cable 19. A conventional electrical control box 20 is mounted upon the bench-plate 17, with the operating gear-shift and reversing levers 20a, 20b turned forwardly for the convenience of the operator. The brake lever 21 for operating the conventional brakes (not shown) is also extended into convenient position within the tonneau.

The rear wheels 7 of the car include the usual drive assembly of axle and differential housings 7a, bolted together as at 7b, and brake drums 21a, which housings inclose the rear axle shafts, differential gears and brakes, and which are not here specifically shown as same comprise merely conventional devices. The housings 7a are supported in place at the lower ends of bracket or hanger plates 5g, to which the housings 7a are rigidly attached by welding or otherwise, as indicated at 5h. The usual braking conduits, cables and connections (not here shown) are operatively connected or associated with the brake lever 21 within the tonneau and whereby the braking elements and shoes within the drums 21a are also controlled. A tool box 22 is mounted at the rear end of the chassis 5 for carrying drill bits or other tools. The tram-car is driven by means of an electric motor 23 supported in position on hangers 23a mounted upon and extended from the chassis, and the drive shaft of this motor is connected in the usual manner with the differential drive gearing within the central housing 7a. Electrical energy is supplied to the motor 23 through leads within the cable 19, the ends of these leads being provided with suitable plugs and couplings for connecting with the usual outlets within the mine and with the complementary connecting elements of the motor. These connecting elements are conventional and not here specifically shown. Through the use of the long electrical leads as inclosed within the cable 19, the car may be conveniently moved from place to place within the mine for drilling operations.

An elongated drill pedestal plate 24 is extended across the rear end of the chassis 5, forwardly of the rear wheel 7, the ends 24a of this plate being projected laterally of the beams 5a, and being braced and supported by the angular brackets 24b. The plate 24 is suitably anchored by welding or otherwise to the beams 5a, and similarly the brackets 24b are secured to the outer sides of the beams and to the ends of the plate 24. The extended ends 24a are rounded off as shown in Figure 2, and these ends are pierced through in circular alignment with a plurality of regularly spaced adjustment holes 24c.

A pair of conventional mine drills 25 are provided, the same including the circular base plates 25a, pedestals 25b, tubular columns 25c pivoted at 25d to the pedestals 25b for vertical movement and adjustment, drill motors 25e and drill chucks 25f pivotally and adjustably mounted at 25g to the outer ends of the columns 25c, and the drill column elevating motors 25h mounted at the bases of the columns for raising and lowering same, the said drill motors and elevating motors being electrically energized in the usual manner by leads extended for that purpose, no invention being claimed in respect of the scheme of electrical extensions, leads and connections. The base plates 25a supporting the pedestals 25b are rotatably mounted upon the ends 24a of the plate 24 by means of heavy pivot bolts 26 extended centrally down through the plates 25a and through the ends

24a of the plate 24. As means for releasably locking the rotatable drills 25 at any desired point of horizontal rotation relative to the pedestal plate 24 upon the ends of which the drills are mounted in the manner described, latching devices 27 are conventionally provided and mounted upon one side of the pedestals 25b, said devices including latch bolts 27a slidably mounted through lugs 27b and adapted at its lower end to selectively engage any one of the apertures 24c of the ends 24a of the plate 24, thus locking the drill in any desired operative position. The latch bolts 27a are operable by levers 27c. Conventional forms of removable covers (not here shown) may as a matter of course, be placed over any of the otherwise unprotected conventional electrical units or devices employed in the tram-car assembly.

In operation the tram-car is driven to any desired work point in the mine with the drills in their lowered positions. The drill columns 25c are then rotated by hand to the desired direction and are elevated also as desired by means of the motors 25h, after which the drills are latched to position and are set to work by energizing the drill motors 25e. Power is supplied to the several motors through the long electrical cables and leads as inclosed in the cable 19, which may be made as long as desired, and thus quite a stretch of work area is afforded with one setting of the tram-car.

While I have herein shown and described a preferred form of the tram-car together with specific structural features thereof, the embodiment shown as well as the structural details, may be changed or modified as desired within the scope of the claims.

I claim:

1. A tram-car of the kind described, the same comprising an oblong body frame carried upon pairs of front and rear wheels and axles, the front axle elements being shorter than the rear axle and the wheels thereon being steerable, the body frame including side beams supported upon the said axles and extended substantially forwardly and outwardly along the outer sides of the front wheels and rearwardly and inwardly along the inner sides of the rear wheels, cross braces connecting the side beams, a vertically positioned rear end cross plate connecting the side beams adjacent their rear ends, a vertically positioned frontal cross plate connecting the side beams above the front axle, the ends of this frontal plate being cut out through their lower margins for seating over the frontal wheels, side plates anchored at their upper margins to the forward ends of the side beams of the body frame, a forwardly disposed floor section supported between the lower margins of the side plates pendant from the forward ends of the side beams of the body frame, a rearwardly disposed floor section supported between the lower margins of the rear ends of the side beams of the body frame, bench or seat plates mounted flatly and horizontally along the inner sides of the frontal ends of the side beams of the body frame and of the said frontal cross plate, for completing a tonneau at the forward end of the car adapted for carrying an electrical power line and control elements, and a tool box mounted at the rear end of the chassis.

2. In a tram-car according to claim 1, means on the rear end of the car for supporting and carrying conventional mining drills, and means for operating said drills.

3. In a tram-car according to claims 1 and 2,

the means for supporting the said mining drills comprising an elongated drill pedestal plate extended and anchored across the rear ends of the side beams of the body frame of the car, the ends of said beams being projected laterally and being adapted for mounting and operatively supporting vertically thereon such conventional mining drills.

WM. B. MANNING.
